(57) **CLAIM**

The ornamental design for a gutter cleaning device, as shown and described.

DESCRIPTION

FIG. 1 is a perspective view of a cleaning head portion of a gutter cleaning device.

FIG. 2 is a right side view thereof, showing the cleaning head portion of FIG. 1;

FIG. 3 is a left side view thereof, showing the cleaning head portion of FIG. 1;

FIG. 4 is a front side view thereof, showing the cleaning head portion of FIG. 1;

FIG. 5 is a rear side view thereof, showing the cleaning head portion of FIG. 1;

FIG. 6 is a top side view thereof, showing the cleaning head portion of FIG. 1;

FIG. 7 is a bottom side view thereof, showing the cleaning head portion of FIG. 1;

FIG. 8 is a perspective view thereof, showing the cleaning head portion shown in FIG. 1. The gutter cleaning device is now being illustrated with a fluid supply tube, in an extended configuration;

FIG. 9 is a right side view thereof of FIG. 8;

FIG. 10 is a left side view thereof of FIG. 8;

FIG. 11 is a front side view thereof of FIG. 8;

FIG. 12 is a rear side view thereof of FIG. 8;

FIG. 13 is a top side view thereof of FIG. 8;

FIG. 14 is a bottom side view thereof of FIG. 8;

FIG. 15 is a top side view thereof of FIG. 8, illustrating the fluid supply tube in a folded configuration; and,

FIG. 16 is a bottom side view thereof of FIG. 8, illustrating the fluid supply tube in a folded configuration.

The broken away symbols in the drawings indicate that any portion of the article beyond what is shown forms no part of the claimed design.

The broken lines in the figures represent the environment and features of the Gutter Cleaning Device that form no part of the claimed design.
